UNITED STATES PATENT OFFICE

2,609,401

NITRATION OF SATURATED ALIPHATIC HYDROCARBONS

Henry B. Hass, Forest Hills, N. Y., and Lloyd G. Alexander, Novman, Okla., assignors to Purdue Research Foundation, La Fayette, Ind., a corporation of Indiana

No Drawing. Application May 26, 1951,
Serial No. 228,537

11 Claims. (Cl. 260—644)

1

This invention relates to the nitration of saturated aliphatic hydrocarbons. More particularly, it pertains to the production of nitro alkanes by the vapor phase nitration of saturated aliphatic hydrocarbons of the paraffin series at elevated temperatures by means of nitric acid, oxides of nitrogen, and the like, in the presence of regulated amounts of molecular oxygen.

Numerous efforts have been made in the past to develop a satisfactory method of obtaining nitro alkanes. The most effective previously disclosed processes are those of Hass et al. described in U. S. Patent Nos. 1,967,667, 2,071,122, and 2,206,813, pertaining to the vapor phase nitration of paraffin hydrocarbons such as ethane, propane, butane, and the like, by means of nitric acid or nitrogen dioxide, and that of Landon, described in U. S. Patent No. 2,161,475, pertaining to the nitration of methane by means of nitric acid.

All of the prior art processes are open to a number of serious objections, one of the most important of which has been the low conversions and yields of products obtained based on the nitric acid used in the process. Because of its cost, corrosiveness, and the like, it is highly desirable to use as small a quantity of nitric acid as possible. We have now discovered that the conversion of nitric acid to nitro alkanes as well as the production of valuable oxidation products when paraffin hydrocarbons are nitrated in the vapor phase can be materially increased by effecting the vapor phase nitration of the hydrocarbons in the presence of molecular oxygen in regulated amounts under certain restricted conditions of time and temperature. This is accomplished by the introduction of the oxygen in such a way as to cause consecutive or simultaneous reaction of the hydrocarbons with oxygen and the nitrating agent.

The use of oxygen in the manufacture of nitro alkanes by the vapor phase nitration of paraffin hydrocarbons has been generally referred to in the Hass et al. U. S. Patent No. 1,967,667, referred to above, where in discussing various methods whereby the yield may possibly be increased, they say "if desired, air or oxygen may be mixed with the hydrocarbons (such as isobutane), in order to reoxidize the oxides of nitrogen to nitric acid; but if this is done, care must be taken to avoid explosive proportions." No further directions or details, however, are given. That the disclosure of this patent is obviously different from our present invention is evident from a consideration of the following facts. If the quoted statement

is interpreted to mean that the improvement in yield is effected by the addition of the oxygen or air and carrying out the procedure in such a manner as to oxidize the oxides of nitrogen to nitric acid and thereby increase the percent conversion to nitro alkanes on the basis of the total amount of nitric acid consumed, it is obvious that the oxidation of the oxides of nitrogen to nitric acid must be carried out under conditions different from those disclosed in the cited patent for the conversion of the saturated aliphatic hydrocarbons to nitro alkanes. Calculations based on the data of Bodenstein (Zeitschrift fur Physik. Chem., 100, 68 (1922) show that at 420° C., the approximate nitration temperature used by applicants, with a nitric oxide content of 5 per cent and an oxygen content of 20 per cent, the oxidation of the nitric oxide would be less than 3 per cent complete in 1.5 seconds. Actually, the conversion would be much less than this because the average percentages of nitric oxides and oxygen in the reactor would be much less than those assumed. A low temperature and a long contact time of the order of several hundred seconds would be necessary to effect substantial oxidation of the nitric oxide.

If, on the other hand, it is assumed that the above-cited statement means that some undetermined amount of oxygen is added to the reaction mixture of the type disclosed in the specification of the cited patent and that the nitration reaction is then carried out as disclosed therein, the improved results claimed by applicants will not be obtained and, as a matter of fact, the addition of oxygen to the reaction mixture often leads to drastically reduced conversions. The cited patent mentioned a mole ratio of hydrocarbon to nitric acid of 2 to 1 (a weight ratio, in the case of isobutane of 1.84 to 1). In the use of oxygen according to applicants' claimed process in order to give increased conversions of the nitrating agent to nitro alkanes, considerably higher weight ratios of hydrocarbons to nitrating agents are necessary, i. e., of the order of from 8 to 25 moles of hydrocarbon per mole of nitrating agent.

The improved process whereby we obtain increased conversions and yields of both nitro alkanes and oxidation products such as alcohols, aldehydes, acids, etc. consists essentially in conducting the vapor phase nitration of saturated aliphatic hydrocarbons at temperatures ranging from 250° C. to 550° C. with a nitrating agent such as nitric acid in the presence of molecular oxygen, the hydrocarbon being used in a propor-

tion of from 8 to 25 moles per mole of nitrating agent and the oxygen being employed in concentrations that do not produce explosive mixtures and preferably in an amount equivalent to 5 to 40 per cent by volume of the hydrocarbon used. By carrying out the nitration under such conditions the conversions to nitro alkanes, based on nitric acid, are increased by as much as 100% over the conventional method of nitration in the absence of oxygen. Such increases in conversions and yields permit the production of nitro alkanes at materially lower costs because of increases in plant capacity, lower raw material cost, and lower labor costs. It is obvious, therefore, that even relatively low increases in conversions are of great importance in the production of relatively expensive materials such as the nitro alkanes.

Our process is, in general, applicable to the nitration of saturated aliphatic hydrocarbons containing from 11 to 4 carbon atoms, such as methane, ethane, propane, butane and isobutane.

Our process may be satisfactorily carried out over a wide temperature range, say 250° C. to 550° C., depending upon the hydrocarbons being nitrated, the products desired, and other conditions. However, the reaction time must be altered in accordance with the temperature used, substantially longer time being required for the lower temperatures, and, in general, the higher the temperature employed, the shorter will be the contact time for optimum conversion of nitric acid to nitro alkanes. In general, the contact times used when molecular oxygen is present do not differ substantially from those used in nitration carried out in the absence of oxygen. Accordingly, in carrying out our improved process, the temperatures, reaction times, and space velocity are regulated in the same general manner as in the prior art processes.

The molecular oxygen used in our process may be added either as substantially pure oxygen or as air containing an equivalent amount of oxygen. Other oxygen-containing gases may also be employed so long as the mixture contains no other gas which reacts under the conditions of the operation with the reactants or the products of the reaction or which interferes with the recovery of the desired products from the reaction mixture.

The optimum time of contact for a given reaction temperature can most conveniently be determined for a given reaction mixture by regulating the time of contact for the reaction mixture at the selected reaction temperature so as to maintain the acidity of the reaction products within a relatively narrow range. Since water is one of the reaction products of the nitration reaction, and the nitro alkanes are in all cases at least partially immiscible with water, the liquid reaction products separate into two layers. The titratable acidity of the aqueous layer constitutes a convenient measure of the acidity of the reaction products, and this value may be used as a basis for the control of the time-temperature factor. If the acidity of the aqueous layer of the reaction products rises above the desired operating range, the reaction temperature should be increased, or the contact time increased (space velocity decreased), or both of these changes may be made simultaneously. Similarly, if the acidity of the aqueous layer drops below the desired operating range, the reaction temperature should be decreased, or the contact time should be de-

creased (space velocity increased), or both of these changes may be made simultaneously. Since it is usually desirable to operate at constant space velocity, it is most convenient merely to adjust the reaction temperature in accordance with the acidity of the aqueous layer. Very small adjustments in temperature will cause relatively large fluctuations of the acidity, and the temperature adjustments should therefore be made gradually. The acidity of the aqueous layer of the product (expressed in normality), should be maintained within the range of 0.1 N to 1.5 N in order to obtain best results. The optimum within this range, in any given case, will depend upon the particular alkane being nitrated, and on the composition of the reaction mixture. This general procedure is more completely disclosed in U. S. Patent No. 2,327,964 by Edward B. Hodge, granted August 24, 1943.

20 The amount of molecular oxygen used in our process is determined by several considerations. In the first place, care must be taken to avoid explosive proportions. In the second place, the use of too large a proportion of oxygen may 25 cause the liberation of an excessive amount of heat and thus lead to lowered conversions through lack of adequate temperature control. Since, however, the latter factor is affected some- 30 what by the reactor design, it is obvious that the amount of molecular oxygen which can be used depends to some extent upon the kind of equipment used. Also, the use of a larger proportion of hydrocarbon in general gives better temperature control and thus permits the use of larger 35 proportions of oxygen. We have generally found that the use of an amount of oxygen equivalent to 5 to 40 per cent by volume of the hydrocarbons being used gives most satisfactory results consistent with safety. However, we have found no 40 upper limit to the increase of conversion as the proportion of oxygen is raised toward the explosive limit.

45 The process of using oxygen in our improved process may be varied somewhat without departing from the concepts of our invention. For example, oxygen may be added to the hydrocarbon before or after the introduction of the nitric acid. We have generally thought it advantageous, however, to vaporize the nitric acid into the hydrocarbon and then to add the oxygen to this mixture before heating to reaction temperature. On other occasions we have found it advantageous to preheat the oxygen-hydrocarbon mixture for several seconds at a temperature of 50 from 300 to 500° C. before adding nitric acid. The concentrations of the nitric acid used may be varied over a wide range without materially affecting the results, 35% nitric acid having given equally as good results as the 70% nitric acid used 55 in the examples given below.

Although we prefer to use nitric acid vapor as the nitrating agent in our process, nitrogen dioxide may also be used and oxygen exerts the same beneficial effect when employed with this nitrating agent. In general, the conditions for using nitrogen dioxide in our process are the same as those employed when nitric acid is used. However, the conversions of nitrogen dioxide to nitro alkanes are somewhat lower than those obtained with nitric acid under analogous conditions.

As previously indicated, our process gives rise not only to increased conversions and yields of nitro alkanes but also to increased formation of 75 oxidation products of the hydrocarbon, being

used. The increased amounts of these oxidation products represent one of the valuable advantages of our process in view of the fact that it gives rise to the formation of sufficient products of this character to justify their recovery from the water soluble fraction of the nitration reaction. Among these oxidation products may be mentioned formaldehyde (from methane) and formaldehyde and acetaldehyde from higher hydrocarbons. The amount of these aldehydes are substantially increased by the use of oxygen. Other valuable oxidation products such as alcohols and acids are also formed.

Our process will be illustrated by the following examples:

EXAMPLE I

A reaction mixture consisting of 8 moles of propane and 1 mole of 67.0% nitric acid was passed in the vapor phase through a reactor consisting of a forty foot coil of "Pyrex" glass tubing (7 mm. diameter) immersed in a fused salt bath at a temperature of 425° C., the contact time being about 1.5 seconds. The addition of oxygen to the propane-nitric acid reaction mixture in varying proportions caused increases in conversions as shown in the table below.

Table I

Oxygen in Propane-Oxygen Mixture, Percent	Conversion of Nitric Acid to Nitro Alkanes, Percent	Formaldehyde Produced per Gram of Nitro Alkane, grams
0	32	0.14
10	45	0.25
15	54	0.25
20	58	0.27
25	61	0.24

Other water soluble oxidation products were also present.

EXAMPLE II

Ethane was nitrated with nitric acid in the vapor phase in the same reactor described in Example I. The molecular ratio of ethane to nitric acid was 12 to 1. The salt bath temperature was 430° C. and the contact time was about 1.5 seconds. The addition of oxygen caused an increase in conversion of nitric acid to nitro alkanes as shown below.

Table II

Oxygen in Ethane Oxygen Mixture, Percent	Conversion of Nitric Acid to Nitro Alkanes, Percent
0	28
20	54

EXAMPLE III

Methane was nitrated with nitric acid in the vapor phase in an apparatus of the type described in Example I at a temperature of 435° C. and a contact time of about 1.7 seconds. The molecular ratio of methane to nitric acid was about 15 to 1. The conversion of nitric acid to nitromethane was increased from 17.6% to 24.2% by the addition of oxygen when the oxygen content of the methane-oxygen mixture was 15%.

EXAMPLE IV

Propane was nitrated in the vapor phase with nitrogen dioxide in an apparatus of the type described in Example I, the temperature of the salt

bath being 410° C. and the contact time about 1.7 seconds. The molecular ratio of hydrocarbon to nitrogen dioxide was about 10 to 1. Addition of 3.1 moles of oxygen per mole of nitrogen dioxide increased the conversion to nitro alkanes from about 14% to about 25%.

The effect of variations in temperature and proportions of oxygen used in the nitration of propane are further exemplified in Table III which follows. It will be noted that in experiment No. 46 reported in this table the oxygen used was introduced in the form of air.

Table III

¹ Ratio of the exit gas volume to the inlet gas volume.

² As air.

The use of oxygen in the vapor phase nitration process not only affects the conversions but also the ratios of the amounts of the various nitro alkanes produced. This is illustrated in Table IV below, showing the nitration of propane.

Table IV

It is to be understood, of course, that we are not limited to the specific operating procedures set forth in the above specific examples since various modifications of the procedure set forth therein will naturally occur to those skilled in the art. For example, the process may be operated in a cyclic manner if desired. Various methods of bringing the reacting gases to the desired reaction temperature may be employed. More dilute solutions of nitric acid than those shown in the specific examples may also be used. The reaction may be carried out at more elevated pressures than those shown. Still other variations common to the prior art may be employed and it is distinctly understood that we may so vary our claimed invention so long as the particular improvement hereinabove disclosed and covered by the appended claims is followed.

This application is a continuation-in-part of our copending application Serial No. 15,504 filed March 17, 1948, now abandoned.

Now having disclosed our invention, what we claim is:

1. In a process for the production of improved yields of nitro alkanes and oxidation products of paraffin hydrocarbons by the vapor phase nitration of saturated aliphatic hydrocarbons containing from 1 to 4 carbon atoms, the improvement which comprises contacting at elevated tempera-

tures, oxygen, with a saturated aliphatic hydrocarbon containing from 1 to 4 carbon atoms and a material selected from the group consisting of nitric acid and nitrogen dioxide said hydrocarbon and said nitrating agent being in a molar ratio ranging from 8 to 1 to 25 to 1 and maintaining said mixture at said elevated temperatures for a sufficient period of time to permit substantial nitration of the hydrocarbons but not substantial oxidation of nitric oxide to nitrogen dioxide.

2. The process of claim 1 wherein the elevated temperature ranges from 250° C. to 550° C.

3. The process of claim 1 wherein the molecular oxygen is present to the extent of five to forty per cent by volume of the said saturated aliphatic hydrocarbon.

4. The process of claim 1 wherein the molecular oxygen is present in the range of concentrations which do not give explosive mixtures.

5. The process of claim 1 wherein the said reaction mixture is maintained at temperatures ranging from 250° C. to 550° C. and the time of reaction is regulated whereby the acidity of the aqueous reaction products is maintained at a substantially constant value which is between 0.1 N to 1.5 N.

6. In a process for the production of nitro alkanes and oxidation products of paraffin hydrocarbons by the vapor phase nitration of propane, the improvement which comprises contacting at elevated temperatures, oxygen, with propane and nitric acid said propane and said nitrating agent being in a mole ratio ranging from 8 to 1 to 25 to 1 and maintaining said mixture at said elevated temperatures for a sufficient period of time to permit substantial nitration of the paraffin but not

substantial oxidation of nitric oxide to nitrogen dioxide.

7. The process of claim 6 wherein the molecular oxygen is present to the extent of five to forty per cent by volume of the said propane.

8. The process of claim 6 wherein the elevated temperature ranges from 250° C. to 550° C.

9. The process of claim 6 wherein the elevated temperature ranges are from 250° C. to 550° C., the oxygen is present to the extent of 5 to 40% by volume of the said propane, and the said reaction mixture is maintained at said reaction temperature for a regulated period of time such that the aqueous reaction products have an acidity within the range between 0.1 N and 1.5 N.

10. The process of claim 6 wherein the saturated aliphatic hydrocarbon is ethane.

11. The process of claim 6 wherein the saturated aliphatic hydrocarbon is methane.
